UNITED STATES PATENT OFFICE.

LUCIAN W. BUGBEE, OF SOUTHBRIDGE, MASSACHUSETTS.

GRINDING-MACHINE.

1,113,930.

Specification of Letters Patent.

Patented Oct. 13, 1914.

Application filed October 8, 1912. Serial No. 724,513.

To all whom it may concern:

Be it known that I, LUCIAN W. BUGBEE, a citizen of the United States, residing at Southbridge, in the county of Worcester and State of Massachusetts, have invented certain new and useful Improvements in Grinding-Machines, of which the following is a specification.

My invention relates to improvements in grinding tools, and has particular reference to an improved device for use in grinding individual cylinder or toric lenses.

The leading object of my invention is the provision of a simple, durable, efficient and inexpensive tool of this character which shall be so constructed that the various parts thereof are interchangeable and may be readily replaced in case of undue wear or breakage of said parts, whereby the life of the tool as a whole will be prolonged to a maximum.

A further object of my invention is the provision of a tool of this character in which the grinding lap and block may be quickly and easily removed and changed without the necessity of employment of any tools whatever.

Another object of my invention is the provision of a device of this nature in which the pivot or main wearing points of the structure will be satisfactorily protected to prevent any access of the grinding or abrasive material thereto and thus to eliminate undue wearing at these points.

Other objects and advantages of my improved tool should be readily apparent by reference to the following description taken in connection with the accompanying drawings, and it will be understood that I may make any modifications in the specific details of construction shown and described within the scope of the appended claim without departing from or exceeding the spirit of my invention.

Figure I represents a perspective view of my tool proper. Fig. II represents a vertical longitudinal sectional view thereof. Fig. III represents a perspective view of one of the guide rods of my structure. Fig. IV represents a perspective view of the lower grinding member employed in conjunction with my tool, and Fig. V represents a fragmentary sectional view of a slight modification of the pivot bearing.

In the drawings, the numeral 1 designates the main or basal portion of my structure

having the socket 2 formed in the under side thereof to receive a rotating spindle for actuating the structure, said portion 1 having depending therearound the frusto-conical or downwardly flaring flange 3 adapted to cause the abrasive material to slide outwardly and away from the bearings of the spindle which fits into the socket 2. Rising centrally from the base member is a reduced upwardly tapering spindle portion 4 adapted to fit into the socket 5 of the base 6 of the tool 7 which I have shown in the drawings as forming the lap or grinding member for operating upon a lens, although it will be understood that if desired the lens may be mounted upon this device. To insure correct positioning of the tool at all times but to permit of ready removal when desired, I have embedded in the spindle 4 the laterally projecting pin or lug 8 which is adapted to be received in the slot 9 extending outward through the wall 6 which surrounds the socket 5, the tool when placed on the spindle with the said slot 9 over pin 8 being thus in correct position relative to the main structure.

As will be understood by those conversant with the art of grinding cylinder, toric and like lenses, it is essential that these lenses be ground with a certain curve in one direction and a certain different curve in the opposite direction, and it is further necessary to see that during the grinding operation there is no variance as to the axes of these curves as such a variance would prove fatal to the correct grinding of the lenses. My structure, as above stated, is for use in so grinding lenses, and the interlocking lug and slot thus described insures the correct positioning of the lap. To insure the exact positioning of the block on which the lens is mounted relative to the lap I pivotally mount on the base member 1 the annulus or ring 10 having extending upward therefrom at diametrically opposite points the lugs 11 each of which has a pair of sockets 12 formed therein and is split by the kerf 13 to form a pair of slightly spaced semi-resilient furcations each having a portion of the sockets 12 therein. These sockets may be either angular or circular in form and are adapted to receive the lower ends of the guide members 14 which extend upward in parallel relation a considerable distance above the furcated lugs. To secure the said guides 14 in place and yet permit of the removal

thereof either to entirely replace the same or to permit of placing a new face inward to receive the wear of the lap handle or guide rod 15, I loosely engage in one of the 5 furcations of each lug a screw or like clamping device 16 whose head bears against said furcation and whose other end has threaded engagement with the opposite furcation, tightening of the screw drawing the semi- 10 resilient furcations toward each other and thus narrowing the kerf and the width of the sockets and securely clamping the lower ends of the guides in place.

I have previously mentioned that the ring 15 or annulus is pivotally secured to the base, the exact method of forming this pivotal connection will be best understood by reference to the section shown in Fig. II, from which it will be seen that there extend outward 20 from the shield member 3 at diametrically opposite points the lugs 17 having preferably embedded therein the removable bearing blocks 18, into which fit the inner ends of the pivot screws 19, said screws extending inward from the annulus or ring 25 with which they have threaded engagement, lock nuts 20 being engaged on the outer ends of the screws for securing the same in desired adjusted position. It will thus be seen that the screws may be quickly and easily removed when the ring and guides 30 may be lifted off of the base portion for replacement or cleaning, if the bearing blocks are too much worn, the same being readily removable, while setting of the screws in desired adjusted position and in correct engagement with the bearings 18 pivotal 35 mounts the ring in desired position relative to the lap bearing spindle 4.

40 In the grinding of a lens on my device abrasive is placed on the portion 7 of the lap and naturally during the operation of the structure said abrasive will drip or drop down from the lap and on account of the 45 centrifugal force caused by the rotation of the complete tool this abrasive would naturally tend to get on the pivot screw or bearing and thus quickly wear out these bearing points. To prevent an action of this nature 50 I form at the end of each lug 17 the semi-circumscribing outwardly projecting flange 21 which projects upward into a groove or recess 22 formed for this purpose in the un-

der portion of the ring or annulus and guide 55 ing, the interlocking of the flange and groove being sufficient to prevent, under ordinary circumstances, access of abrasive material to the bearings. In some instances it will be found desirable, however, to take 60 additional precautions against undue wearing of the pivot bearing, and when this is the case I may elongate the bearing aperture in which the block 18 fits in such manner as to provide the integral or inserted cone bearing face engaged by the tapered end 65 of the screw and adjacent this a socket to receive a washer member 23, said washer being preferably of some fibrous material as shown in Fig. V which will tightly engage 70 the body of the pivot screw to prevent absolutely any entrance of abrasive material into the bearing proper, a second washer of metal or other stiff substance 24 holding the fibrous washer in place. In this form it is practically impossible for any abrasive to get into 75 the bearing, while an aperture 25 formed in the underside of the depending shield 3 and connecting with the cone bearing permits of oiling thereof as may prove necessary.

From the foregoing description taken in connection with the accompanying drawings the construction of my improved grinding tool and the possibility of readily assembling, disassembling and replacing of the parts thereof should be readily understood. 80

I claim:

A tool of the character described, including a base, a shield member depending around and flaring outwardly from said base, said shield having portions projecting from diametrically opposite sides thereof, said portions having pivot bearings formed therein, an annulus having pivots adjustably engaged in the said bearings, said annulus having lugs projecting upwardly therefrom at diametrically opposite points thereon and disposed above the pivots carried by the annulus, and spaced guide members removably secured to and extending upward from the 90 said lugs of the annulus. 95

In testimony whereof I affix my signature in presence of two witnesses.

LUCIAN W. BUGBEE.
